UNITED STATES PATENT OFFICE.

CHARLES ALTON PFAHL, OF AKRON, OHIO, ASSIGNOR TO THE B. F. GOODRICH COMPANY, OF NEW YORK, N. Y., A CORPORATION OF NEW YORK.

DESIGN FOR A PNEUMATIC TIRE TREAD.

Application filed January 25, 1923. Serial No. 4,991. Term of patent 14 years.

To all whom it may concern:

Be it known that I, CHARLES A. PFAHL, a citizen of the United States, residing at Akron, in the county of Summit and State of Ohio, have invented a new, original, and ornamental Design for a Pneumatic Tire Tread, of which the following is a specification, reference being had to the accompanying drawing, forming a part thereof.

The drawing is a perspective view of a pneumatic tire bearing my new design for a pneumatic tire tread.

I claim:

The ornamental design for a pneumatic tire tread as shown.

CHARLES ALTON PFAHL.
